UNITED STATES PATENT OFFICE.

VERNON D. STEWART, OF PARIS, ILLINOIS.

NOSE RING FOR LIVESTOCK.

Application filed September 26, 1923. Serial No. 664,898.

My present invention relates to nose rings for live stock, particularly for hogs, and is an improvement upon U. S. Letters Patent No. 1,136,496, issued under date of April 20, 1915, to U. G. Stewart, then of Paris, Illinois.

It has for an object to facilitate the initial bending, and to insure greater accuracy and uniformity in ring formation.

As a further object the present invention contemplates the production of rings, of the character indicated, capable of application to the snout of an animal with speed, accuracy and precision, and with a greater degree of effectiveness than heretofore.

A further object is the production of comparatively inexpensively nose rings of extremely simple, but practical construction, which are at once durable and peculiarly efficient in the performance of their intended functions.

As a still further object the present ring structure, when properly applied to the snout of a hog, is designed, arranged and adapted to prevent rooting, fence-lifting, chicken eating, or in case of a vicious hog attacks upon others in the same field or pen.

Other objects and advantages of the present invention will be apparent to persons engaged in the industry to which it relates.

The invention will be hereinafter particularly described and pointed out in the claims following.

In the accompanying drawings which form part of this application for Letters Patent, and whereon corresponding reference characters indicate like parts in the several views:

Figure 1 is a perspective view of an unformed or open ring embodying my invention, having combined therewith a special form of interfering prong;

Figure 2 is a side elevation of parts shown by Figure 1;

Figure 3 is a top plan view of structure also with ring unformed;

Figure 4 is a top plan view of one triangular ring as finally closed in operative position, from a blank indicated by dotted lines; and

Figures 5 and 6, respectively, indicate in plan, two of many possible ring shapes closed into final and operative position, the interfering prong in both instances appearing in section.

Reference being had to the drawings and characters thereon, 1 indicates the body of my improved nose ring formed of relatively stiff wire, and of any desirable contour 60 so long as substantially ring shaped, but in any event terminating in reversely disposed and oppositely sharpened or beveled extremities 2, 2, constituting entering or piercing prongs.

At approximately its center this ring blank or body 1, is formed with an inwardly disposed kink 3, thus resulting in slight but perceptible shoulders 4, 4, upon each side thereof. This special arrangement and construction of central kink 3, together with the flanking shoulders 4, 4, has been found in practice to greatly facilitate the proper closing of rings, and their symmetrical formation, as shown by Figures 4, 5 and 6.

Crossing the ring blank or body portion 1, directly in front of its kink 3 aforesaid, is a combined spur or goad 5, and an interfering prong 6 formed by a continuation of 80 said spur, and for purposes which will later appear.

Obviously the last mentioned elements 5 and 6 may be variously formed and of various proportions according to special requirements for use upon pigs, shoats, hogs or other animals, but, as will be observed, the present illustrations disclose a prong 6 of unusual length, and of cyma-reversa curved form, especially arranged and 90 adapted for use upon chicken-eating and vicious hogs.

The said combined spur 5 and curved prong 6 is preferably secured to the inner central area of blank or body 1, directly 95 opposite the kink 3 by welding these two members securely together, and by this process a certain amount of crystallization or hardness between shoulders 4, 4 is set up, which also contributes to the desired symmetrical formation of the finished ring, and assists in starting the ring-bending operation from both sides at one and the same time.

In practice these rings are applied by 105 closing and overlapping their beveled extremities 2, 2, directly through the cartilage between the nostrils of a hog, for example, or other animal, the ordinary ringer pincers (not shown) being employed for this purpose; and, when so applied, the position of prong 6 in use upon the snout of the ani-

mal when standing erect, is approximately parallel with the ground. In this relation of parts it is obvious that any attempt at rooting or fence-lifting reacts directly upon the hog itself, because depression of the prong 6 fulcruming upon the inner portion of ring body 1, causes the lower extremity of spur 5 to goad into the comparatively tender end of the animal's snout above the mouth to promptly curb his ambitions.

Because of the extended length and peculiar shape of the said prong 6 also, it is correspondingly difficult or impossible for hogs equipped with the present device, to reach or overtake chickens, other fowls, or small game as sometimes occurs under ordinary conditions.

In the manufacture of my present nose ring, which is regarded as a distinct practical improvement upon the Stewart Patent No. 1,136,496, experience has demonstrated that the "kink" or "slight indentation" 3, in a ring-blank is necessary to a proper closing and symmetrical formation thereof; to a proper meeting of the sharpened points 2—2; and to a maximum clearance or interior space within its confines when closed.

This term "kink" or "slight indentation" as used in the claims of this application, it may be stated, relates to that portion in Figures 1, 3 and the dotted lines of Figure 4, between the lead lines of reference numerals 4—4, and has a distinct function to perform in the process of making these completed rings, equipped with a cross spur or goad such as 5, and an interfering prong such as 6, to prevent rooting.

That function of kink 3 may be stated as follows: The combined wire spur 5 and

prong 6, is in practice permanently secured to the outer central portion of ring blanks by agency of electric welding, and it has been found that the resulting crystallization so hardens that portion of these rings between the lead lines 4, 4 aforesaid, as to render impossible a proper closing; a symmetrical formation, and the full rounded interior clearance of the ring that is required, unless the slight inward indentation or kink 3 is provided as herein shown and claimed.

Having thus described my present invention what I now claim and desire to secure by Letters Patent is:

1. As an article of manufacture a blank for nose rings having oppositely disposed inturned piercing ends, and an indentation intermediate its ends arranged and adapted to facilitate closing and, when closed, to insure a smooth surface without indentations. 60

2. As an article of manufacture a blank for nose rings having oppositely disposed inturned piercing ends, an indentation intermediate its ends arranged and adapted to facilitate closing, and an anti-rooting prong crossing the ring at an angle to the plane thereof. 65

3. As an article of manufacture a blank for nose rings having oppositely disposed inturned piercing ends, an indentation in the plane of the structure intermediate its ends, and a shoulder upon each side of said indentation arranged and adapted to facilitate closing the ring and, when closed, to insure a smooth surface without indentations. 70 75

In testimony whereof I affix my signature.

VERNON D. STEWART.
